DRINKING CUP WITH HANDLE

Peter Yendrzejowski, Wall, Pa.

Application October 2, 1936, Serial No. 103,750

1 Claim. (Cl. 229—1.5)

This invention relates to paper drinking cups and has for the primary object the provision of a device of this character which has a handle for the convenience of the user and which normally lies in close proximity to a wall of the cup so as not to interfere with the vending of a cup from a machine or the packing of the same in a carton and which may be readily extended for use.

10 With these and other objects in view this invention consists in certain novel features of construction, combination and arrangement of parts to be hereinafter more fully described and claimed.

15 For a complete understanding of my invention reference is to be had to the following description and accompanying drawing, in which

Figure 1 is a perspective view illustrating a drinking cup having a handle constructed in accordance with my invention.

Figure 2 is a top plan view illustrating a cup and the handle.

Figure 3 is a plan view of the blank of the cup showing the handle forming an integral part thereof.

Figure 4 is a perspective view illustrating a cup made from a blank shown in Figure 3 with the handle in a folded position.

Referring in detail to the drawing the numeral 30 1 indicates a drinking cup which may be of any well known construction and has secured thereto a handle 2 to facilitate the handling of the cup by a person. The handle 2 may be folded upon itself to lie in close proximity to the wall 35 of the cup as shown at 3 so that the cup may be vended from a machine without interference from the handle or may be readily packed in a carton with other cups similarly constructed.

While I have shown the handle as being adapted to a cup of conical formation it is to be understood that a handle of the character employed in this invention may be readily adapted to cups of other shapes by having the handle formed integrally with one edge of the cup and the other end suitably secured to the cup adjacent the bottom thereof.

In Figure 3 is shown a blank 4 from which the cup 1 is constructed. The blank has a substantially triangular shaped portion 4 which may be brought into conical shape to form a cup and formed at one corner of the portion 4 is a strip 5 to form the handle and the free end thereof is secured to the cup adjacent to the bottom. The 10 free end of the handle or strip 5 may be cemented or otherwise secured to the body of the cup before the twisting or winding of the flap 6 of the blank into conical shape so that both ends of the handle become firmly attached to the cup. The 15 handle may be folded upon itself as shown in Figure 4, and may be extended to assume the position, as shown in Figure 1, by a simple pull thereon away from the cup so that a person may pass the fingers about the handle in obtaining a grip 20 25 thereon.

Having described the invention, I claim:

A drinking cup comprising a substantially triangular shaped blank adapted to be rolled into conical shape and including a flap adapted to be 30 twisted about the blank after the rolling thereof for retaining said blank in conical shape, a strip formed on one corner of the blank to provide a handle, said strip having its free end secured on the rolled blank with the flap twisted thereover. 35

PETER YENDRZEYOWSKI.
